UNITED STATES PATENT OFFICE.

LEWIS E. WATERMAN, OF ROCKFORD, ILLINOIS, ASSIGNOR TO EMERSON-BRANTINGHAM COMPANY, OF ROCKFORD, ILLINOIS, A CORPORATION OF ILLINOIS.

TWO-ROW LISTER.

1,194,581.

Specification of Letters Patent. Patented Aug. 15, 1916.

Application filed September 16, 1914. Serial No. 862,099.

To all whom it may concern:

Be it known that I, LEWIS E. WATERMAN, a citizen of the United States, residing at Rockford, in the county of Winnebago and 5 State of Illinois, have invented certain new and useful Improvements in Two-Row Listers, of which the following is a specification.

This invention relates to agricultural implements of the type adapted for furrow 10 opening or for plowing, and has more particular reference to listers which employ one or more middle-bursting furrow openers.

One of the primary objects of my invention is to provide a two-row lister of improved and simple construction which will be efficient in operation, strong and durable in construction and which may be manufactured at a low cost.

Another object of my invention is to provide a novelly constructed frame upon which supporting-wheels and earth agitating-implement beams may be adjustably mounted in a simple manner.

A further object is to so mount the supporting-wheels and earth-agitating-implement beams that the supporting-wheels may be independently adjusted laterally of the frame to accommodate them to different widths of rows.

30 Referring to the drawings: Figure 1 is a plan view of my improved lister. Fig. 2 is a vertical longitudinal section taken through the lister on the line 2-2 of Fig. 1, and Figs. 3 and 4 are enlarged detail sections 35 taken on the lines 3-3 and 4-4, respectively, of Fig. 1.

Referring to the drawings it will be seen that the frame of the machine is of rectangular shape comprising front and rear 40 cross-beams designated by the reference characters 5 and 6, respectively, arranged transversely with respect to the line of draft and fixedly connected together by pairs of tie-bars, each pair of which comprises an 45 inner and an outer bar designated by the reference characters 7 and 8, respectively. The cross-beams 5 and 6 which are preferably made of wood are rectangular in cross-section, and the tie-bars are formed of 50 metallic strips having their ends bolted flat to the under side of the beams and their intermediate portions twisted to lie in a vertical plane. The tie-bars are shaped to carry the rear cross-beam higher than the forward 55 cross-beam for the purpose of accommodating

the furrow-opener beams and are depressed intermediate the cross-beams to provide mountings for supporting-wheels, as clearly shown in Fig. 2, the purpose of this construction being hereinafter explained.

A supporting-wheel frame in the form of a casting 9 bolted fixedly to the front cross-bar 5 and braced by hounds 11, extends forward from said cross-bar and is provided at its forward end with vertical-axis journal-bearings 12 in which is journaled a shaft 13, connected to an axle 14 upon which supporting-wheels 15 are mounted. A collar 16 mounted upon the shaft 13 intermediate the bearing 12 is provided with a set screw by 70 means of which the collar may be fixedly connected to the shaft to hold the shaft from axial movement. A clevis 17 fixedly connected to the shaft 13 provides means to which either draft-bars 18 or a tongue (not 75 shown) may be connected; and through this draft connection the front-carrying wheels may be turned upon shaft 13 to guide the implement in either direction.

A crank-axle and a furrow-opener beam 80 are mounted upon each side of the machine frame and, since the construction of these devices at both sides of the frame is identical, a description of the devices at one side will be sufficient for an understanding of the 85 construction and operation of both.

A beam 19 arranged parallel with the line of draft and interposed between the tie-bars 7 and 8 at the under sides of the cross-beams, is bolted fixedly at its forward and rear ends 90 to said cross-beams. The forward end of the beam 19 is fastened to the cross-beam 5 by means of a pair of bolts 21 arranged on opposite sides of beam 19, and having their lower ends bent to extend through apertures 95 in said beam and provided with nuts 22, the bolt shanks extending upwardly through apertures in the cross-beam and being drawn tight by nuts 23 which screw down onto a wearing plate 24 as shown in Fig. 4. The 100 rear end of the beam has bolted at each side thereof an angle plate 25 (Fig. 3) which is connected fixedly with the cross-beam 6 by bolts 26 extending through said cross-beam, wearing plates 27 being interposed between the upper face of the cross-beam and the nuts of the bolts. The beam 19 is of the 105 standard construction and has attached to its rear end a middle-bursting furrow opener 28 of any well known or preferred construc- 110

tion. The cross-beams 5 and 6 are provided with a plurality of laterally spaced bolt holes 30 for the reception of the bolts 21 and 26 so that the beam 19 may be adjusted laterally for different widths of rows. It is obvious that fastening means for the front and rear ends of the beams 19, other than those shown and described, might be used, and that the fastening means might be of such construction that the beams 19 could be adjusted laterally to any position intermediate the tie-bars 7 and 8.

The depressed portions of the tie-bars 7 and 8 are apertured to provide bearings for a crank-axle 29, the shaft portion of which extends beneath the beam 19 and the crank and axle portion of which is located at the outer side of the outer tie-bar 8. A supporting-wheel 31 is journaled on the outer end 20 of the axle. The inner end of the crank-axle shaft is bent upwardly at right angles and flattened as at 32, to accommodate a hand-lever 33 which is rigidly bolted thereto. A toothed segment-bar 34 is bolted to the tie-bar 7 adjacent to the hand-lever and the hand-lever is provided with the usual manually operable latch adapted to engage with said segment bar. It is obvious that by moving the hand-lever 33 backward and forward the crank will be swung in its mounting on the tie-bars to raise or lower the frame and the furrow openers carried thereby, the frame being fulcrumed on the front axle 14. It is also evident that with the hand-lever in a set position as shown in Fig. 2, the position of the carrying-wheel 31 will determine the working depth of the furrow opener. A seat bar 35 is mounted on the rear cross-beam intermediate the hand-levers 32 and carries a driver's seat 36.

Seeding mechanism of any well known or preferred form may be attached to the rear ends of the beams 19, and in the present instance, I have shown merely but one seeding mechanism which is in outline designated by the reference character 37. When the furrow-opener 28 is raised to an elevated position by operating the hand-lever so as to swing the crank-axes forwardly, the seeding mechanism will be likewise raised above the ground.

It will be manifest from the foregoing that a very simple yet strong and rigid frame is produced by the cross-beams and tie-bars arranged in the manner described. It is also obvious that this construction permits the mounting of adjustable supporting-wheels and furrow-opening beams in a very simple manner and also permits each to be independently adjusted without interfering with or disturbing the mounting of the other.

I claim:

1. In an agricultural implement of the character described, the combination of a

frame comprising a front and a rear cross-beam and a pair of spaced tie-bars fixedly connecting said beams at each end thereof, an implement carrying-beam extending in the line of draft intermediate the spaced tie-bars of each pair and fixedly mounted on the cross-beams, a crank-axle mounted on each pair of tie-bars with its axle at the outer side of said bars and having its inner end bent to form a crank portion, a supporting-wheel mounted on each axle, and a lever fixedly mounted on each inner crank portion for swinging its crank-axle to raise and lower the frame.

2. In an agricultural implement of the character described, the combination of a frame comprising a front and a rear cross-beam and a pair of spaced tie-bars fixedly connecting each end portion of the cross-beams, a plow beam extending in the line of draft intermediate the spaced tie-bars of each pair and being adjustably mounted on the cross-beams so as to be movable laterally thereon intermediate the tie-bars, a crank-axle mounted on each pair of tie-bars with its axle at the outer side thereof, a supporting-wheel mounted on each axle, and a lever connected to the inner end of each crank-axle for swinging the same to raise and lower the frame.

3. In a lister plow, the combination of a plow beam, a front and a rear cross-beam mounted on the top of the plow beam, tie-bars connecting the cross-beams and shaped to extend beneath the plow beam intermediate the cross-beams, a crank axle mounted on the tie-bars below the plow beam, a carrying wheel for said crank axle, and means for adjusting the crank axle to raise and lower the plow beam supporting frame.

4. In a lister plow, the combination of a frame comprising a front and a rear cross-beam connected by tie-bars, a plow beam secured to the front and rear cross-beams, said tie-bars being depressed intermediate the cross-bars to form supports below the plow beam for crank axles, crank axles mounted on said supports below the plow beam, carrying wheels mounted on the crank axles, and means for adjusting the crank axles to raise and lower the said frame.

5. In a lister plow, the combination of a plow beam, a front and a rear cross-beam secured to the plow beam, the rear cross-beam being mounted on top of the plow beam, means securing the cross-beams together and providing a support for a crank axle intermediate the cross-beams below the plow beam, a crank axle mounted on said support below the plow beam, a carrying wheel for said crank axle, and means for adjusting the crank axle to raise and lower the plow beam carrying frame.

6. In a lister plow, the combination of a

front and a rear cross-beam joined at their end portions by tie-bars, plow beams secured to the cross-beams and adjustable laterally thereon, said tie-bars carrying crank 5 axle supports below the plow beams, crank axles mounted on said supports below the plow beams, carrying wheels for the crank

axles, and means for adjusting the crank axles to raise and lower the plow beam carrying frame.

LEWIS E. WATERMAN.
